METHOD OF MAKING AN ARTICLE OF
MANUFACTURE

Maurice Fixler, Chicago, Ill., assignor, by mesne assignments, to Fixler Bros., Chicago, Ill., a copartnership consisting of Maurice Fixler and Martin Fixler

Application January 13, 1941, Serial No. 374,160

1 Claim. (Cl. 2—278)

This invention relates to an article of manufacture comprising sheets adapted to be severed into blanks for needlework and to methods of fabricating articles of needlework from such sheets.

An object of the invention is to provide a method of fabricating articles of needlework comprising severing a fabric sheet having spaced figures outlined by hemstitching or the like to form blanks and connecting the resultant blanks by needlework.

Other and further objects of the invention will become apparent from the appended drawing and the following description.

According to this invention, webbed sheets are stitched to outline thereon a plurality of spaced motifs, and the sheets are severed intermediate the motifs. The resultant pieces are trimmed according to the contour of the stitched motif included within each piece. The blanks thus obtained may be arranged in any desired pattern and connected, for instance, by crocheting, to form a variety of decorative articles such as doilies, scarfs, drapes, bed spreads, and the like.

The delineations on a single sheet of fabric may be repetitions of one and the same motif. Whether or not identical as to form or size, the motifs preferably form closed figures, such as triangles, squares, hexagons, octagons, circles, or ellipses, although open figures on the order, for instance, of horse shoes, may also be employed. The stitching outlining the motifs preferably consists of hemstitching or some other type of stitching forming series of small closely spaced perforations whose margins are reinforced by continuous stitches. The stitching may be done in colors.

A single sheet may have outlined thereon any desired plural number of motifs. The blanks are formed by cutting out the motifs leaving a narrow margin of, say, $\frac{1}{8}$ inch around each motif. Blanks from one or several sheets and of similar or contrasting shape, size, or color may then be connected according to any desired pattern by hand crocheting or some other form of knitting or lace. The stitches of the motif form a reinforced margin for the blanks on which the first row of crochet lace or the like may at once be anchored. The perforations of the stitching serve as ready reference points in the distribution of the crocheting stitches around the blank. Crocheting around the margins of the blanks may be joined in the finished article by crocheting stitches or by sewing. The crocheting may be done in colors similar or contrasting to that of the blanks.

In view of the variations possible in size, shape, and color of the blanks and in color and pattern of crocheting, a practically infinite number of patterns can be developed for highly decorative articles of needlework. Such articles can be fabricated easily and simply according to the present invention by any one familiar with the art of crocheting.

The appended drawing shows an illustrative example of the present invention, and more particularly:

Figure 1 shows a fragmentary plan view of a fabric sheet with spaced stitched motifs indicated diagrammatically.

Figure 2 shows a greatly enlarged plan view of a blank severed from the sheet of Figure 1. The nature of the stitching in the motif is shown in some detail.

Figure 3 shows a highly diagrammatical plan view on a small scale of four blanks such as those shown in Figure 2 arranged in a rhomboid pattern.

Figure 4 shows an enlarged fragmentary plan view of blanks such as those of Figure 2 arranged as in Figure 3 and joined by hand crocheting. The stitching in the motifs on the blanks is indicated only by a series of perforations, to show the crocheting more plainly.

As shown on the drawing:

In Figure 1, the reference numeral 10 indicates generally a matricular sheet from which blanks may be cut. The sheet comprises a web 11 having outlined thereon by stitching 12 spaced repetitions of a circular motif.

In Figure 2, the reference numeral 15 indicates generally a circular blank cut from the sheet 10. A margin 16 of about $\frac{1}{8}$ inch is left around the stitching 12. As shown, the stitching 12 defines a series of closely spaced small perforations 17 whose margins are reinforced by stitches. Such stitching may be done on a hemstitching machine or on a schiffli embroidering machine.

Figure 4 shows how the blanks 15 arranged, for instance, in the rhomboid pattern illustrated in Figure 3, may be joined by crocheting 20. Crocheted loops 21 drawn in equal numbers through all the perforations 17 and spanning the margin of the blanks anchor the crocheting 20 to the blanks.

Many embodiments of the principles of this invention other than that illustrated in the drawing are possible, for this invention includes the broad concept of predetermining in a single web a plurality of blanks each including a single motif outlined by marginal stitching, severing these

blanks from the web by cutting the web around the stitching, and joining a plurality of such blanks according to a predetermined pattern by crocheting. It is therefore not my intention to limit the patent granted on this invention otherwise than necessitated by the scope of the appended claim.

I claim as my invention:

In a process of fabricating a piece of needlework from a plurality of predetermined shaped blanks of fabric, the steps of forming in a sheet of fabric a plurality of blanks each of a predetermined configuration encompassed by a border

of needlework having therein a plurality of spaced perforations, severing each blank from the sheet by cutting into the sheet along a line of severance close to but outside of said blank border, and thereafter applying crochet work to said border of the severed blank by fastening same to said blank border and through said perforations thus to center the blank with respect to and to connect it to other blanks in the piece of needlework and whereby the ragged edge of each cut blank is enveloped in and concealed by the crochet work.

MAURICE FIXLER.
